UNITED STATES PATENT OFFICE.

HENRY E. BRANDT, OF NORTH ST. PAUL, MINNESOTA.

SPRAYER-PUMP STRUCTURE.

Application filed March 26, 1923. Serial No. 627,567.

To all whom it may concern:

Be it known that I, HENRY E. BRANDT, a citizen of the United States, residing at North St. Paul, in the county of Ramsey and State of Minnesota, have invented certain new and useful Improvements in Sprayer-Pump Structures; and I do hereby declare the following to be a full, clear, and exact description of the invention, such as will 10 enable others skilled in the art to which it appertains to make and use the same.

This invention relates to a closure device for a receptacle, and particularly to a device for closing a sprayer receptacle and carrying means co-operating with a pump cylinder and plunger rod usually used in such receptacles. Such spraying devices are now extensively used by gardeners, horticulturalists and other persons and usually comprise a 20 closed receptacle having therein a pump cylinder plunger and plunger rod by which the liquid in the receptacle is placed under pressure. The plunger rod is provided with an operating handle and this handle is sometimes used to carry the receptacle.

It is an object of this invention to provide a closure member for the sprayer receptacle which co-operates with the pump cylinder and plunger rod in a simple, novel and efficient manner.

It is a further object of the invention to provide such a closure member having two externally threaded portions, one of which co-operates with a threaded opening in the receptacle, the other of which co-operates with the threaded interior upper end of the pump cylinder, said closure member acting to close both the opening in the receptacle and the opening in the pump cylinder.

It is another object of the invention to provide such a closure member of hollow cylindrical form having an inwardly projecting lug disposed above the bottom of its interior and to provide a plunger rod having means thereon adapted to rotate beneath said lug.

It is more specifically an object of the invention to provide such a closure member having a shouldered recess therein and having an inwardly projecting lug punched out or struck up from the lower portion of the recess and spaced from the bottom thereof, together with a plunger rod reciprocable through the bottom of the closure member having a flange adapted to rotate beneath

said lug with means thereon to contact either side of said lug and a recess therein to pass over said lug.

It is still another object of the invention to provide such a closure member having externally threaded portions of different diameter, thereby forming a shoulder, the smaller of which portions receives the pump cylinder, the upper end of which contacts with said shoulder, the larger diameter of the closure member fitting the threaded opening of the receptacle and the said shoulder contacting a closing gasket therein.

These and other objects and advantages of the invention will be fully set forth in the following description made in connection with the accompanying drawings in which like reference characters refer to the same part throughout the different views, and in which,

Fig. 1 is a view partly in side elevation and partly in section of a portion of the upper end of a sprayer receptacle;

Fig. 2 is a view in vertical section, taken substantially on the line 2—2 of Fig. 1, as indicated by the arrows;

Fig. 3 is a horizontal section taken on the line 3—3 of Fig. 2, as indicated by the arrows;

Fig. 4 is a view in side elevation of the closure member; and

Fig. 5 is a view in vertical section thereof taken on the line 5—5 of Fig. 4, as indicated by the arrows.

Referring to the drawings, a portion of a sprayer receptacle 1 is illustrated which receptacle is shown as of the cylindrical type having a vertical axis, although it is obvious that this receptacle may be of any shape desired. Said receptacle is provided with an opening upon its upper end surrounded by a flange 2 in which is seated and secured by brazing, soldering, or otherwise, a member 3 of substantially cylindrical shape, open at its top and interiorly threaded. The said member 3 has a flange 4 extending inwardly at its bottom portion on which seats a gasket member 4^a, said flange 4 having a central aperture therethrough in which is disposed and adapted to pass a pump cylinder 5.

A closure member indicated as a whole as 6 is provided and comprises a hollow cylindrical member having comparatively thin walls which, as illustrated, has a portion 7

with a threaded exterior and a smaller portion 8 provided with a threaded exterior, said portions thus forming a shoulder which is slightly recessed, as indicated at 9, thus 5 forming a curved edge or corner at the bottom of the portion 7. The bottom of the member 6 is closed save for a central opening 10 extending therethrough surrounded by a downwardly projecting short hub portion 10 11. A tongue or lug 12 is punched inwardly or struck up laterally from one side of the portion 8 and this lug projects inwardly from the interior wall of said closure member substantially in line with the shoulder 15 between the portions 7 and 8. An opening through the side wall of the member 8 is thus formed by said struck-up lug, as clearly indicated in Figs. 4 and 5.

A pump plunger rod 13 is adapted to reciprocate through the opening 10 and this rod carries at its upper end an operating handle 14 having at its lower portion in which the rod 13 is secured, a flange 15, which flange is provided at one side with a 20 recess or cut out portion 16 of a size and shape adapted to pass over the lug or tongue 12. Said flange also has upstanding at another portion thereof, shown as disposed opposite to the recess 16, a lug 17. It will be 25 seen that the flange 15 is adapted to seat in the bottom of the member 6 and rotate beneath the tongue 12 and that the lug 17 will contact with the sides of said lug as the flange, plunger and handle are rotated in 30 one direction or the other. The pump cylinder 5 is formed with an outwardly turned thin edged flange at its top portion and is 35 adapted to be screwed onto the portion 8 of the member 6. The said flange at its top 40 is adapted to fit tightly against the bottom of the recessed portion 9 so that the top of the cylinder is tightly sealed and the opening formed by punching in the lug 12 is closed. The portion 7 of the closure member 45 6 is, as clearly shown in Figs. 1 and 2, adapted to be screwed into the member 3 so that the shoulder below the same or the outer edge of the flange at the top of the cylinder 5 or both contact with the gasket 4^a to 50 form a tight seal and closure for the receptacle 1.

With the described structure, it is clear that when it is desired to operate the pump comprising the cylinder 5, the plunger rod 55 can be turned by handle 14 to bring the recess 16 in alinement with the lug 12 so that the rod can then be reciprocated as desired to operate the pump. When the flange 15 is turned and disposed below the lug 12, the 60 receptacle may, if desired, be lifted and carried by the handle 14, the flange then contacting the bottom of said lug. If it is desired to remove the pump cylinder the flange 15 is rotated beneath the lug 12 by the handle 14 in a counter-clockwise direction and 65

the lug 17 will then contact the side of lug 12 and the closure member 16 will be screwed out of member 3. The pump cylinder, together with the closure member 6 can then be withdrawn from the receptacle. If 70 it is desired to have access to the inside of the pump cylinder, the same can be held in one hand and the handle 14 again turned in a counter-clockwise direction and the lug 17 will then contact the sides of lug 12 and the closure member 6 will be screwed out of the pump cylinder 5. It is thus seen that the handle 14 not only serves to operate the pump and if desired, at times to lift the receptacle, but also forms a means by which 75 both the portion 7 and the portion 8 can be turned and unscrewed from their respective parts. It is obvious that the members 6 can be again screwed into the pump cylinder 5 and into the member 3 by a clockwise turning of the handle 14 when the lug 17 has contact with the other side of lug 12 and turns the member 6 so that it can be readily screwed into place.

From the above description it is apparent that applicant has provided a simple and efficient closure structure for a spraying receptacle. The closure member 6 is preferably formed by being pressed in a die and the tongue 9 punched out from the side thereof, as described. This member can thus be very quickly and inexpensively made. As indicated, the opening formed in the member 8 is no disadvantage as the same is closed when the member 6 is screwed into the pump cylinder. The handle portion 14 is also quite simple and, as described, accomplishes several functions which heretofore have been performed by different members and have been performed with difficulty and inconvenience. With applicant's structure it is a simple and easy matter to disassemble the various parts and to reassemble the same and this advantage is attained by a structure which is simpler and more economical than the structures of the prior art. The parts are preferably made of brass, bronze or some other non-corrosive metal as the spraying solutions sometimes used are quite corroding to certain types of metals. Applicant has, therefore, provided a simple novel apparatus and method of constructing the same and the success of the device has been amply demonstrated in actual practice.

It will, of course, be understood that various changes may be made in the form, details and proportions of the parts and in the sequence of the steps of the method without departing from the scope of applicant's invention, which, generally stated, consists in the matter shown and described and set forth in the appended claims.

What is claimed is:

1. A sprayer having in combination a receptacle having a threaded opening therein

with an inwardly extending annular flange at the bottom of said opening, a pump cylinder adapted to be disposed in said receptacle and passed through said opening, a closure member having two portions with threaded exteriors of different diameters forming a shoulder therebetween and adapted to be screwed respectively in said threaded opening and pump cylinder, a plunger rod reciprocable through said closure member, means on said rod for engaging said closure member to turn the same into or out of both said threaded opening and pump cylinder, and a single packing ring disposed on 10 said annular flange and engaged by said shoulder on said closure member.

2. A sprayer having in combination a receptacle having an opening therein, and a pump cylinder adapted to be disposed in 20 said receptacle and passed through said opening, a closure member threaded into and disposed in said opening having means fitting into said pump cylinder and insertable in and removable therefrom by a turning 25 movement, a handle-equipped plunger rod reciprocable through said member, means on said rod engageable with said member to turn the same into and out of both said opening and pump cylinder, and a gasket 30 disposed in said opening against which said closure member engages to seal said pump cylinder and said receptacle.

3. The combination with a sprayer receptacle having an interiorly threaded opening 35 therein with a flange beneath said opening, and a pump cylinder adapted to be disposed in said receptacle, of a closure member for said receptacle and pump cylinder formed as a cylinder having exteriorly threaded 40 portions of different diameters forming a shoulder therebetween, one adapted to be screwed into said threaded opening and the other adapted to be screwed into the pump cylinder, said shoulder seating on said 45 flange and forming therewith a seal.

4. The structure set forth in claim 3, said closure member being hollow and having a closed bottom save for a central opening therethrough, said member thus having a 50 shouldered recess therein, said member having a lug struck up from the side of the said portion of smaller diameter and projecting inwardly of said recess above the bottom thereof to form a turning means for said member.

5. In a sprayer structure comprising a receptacle having a threaded opening therein and a pump cylinder adapted to pass into said opening, a hollow cylindrical member having exteriorly threaded portions of 60 different diameters forming an exterior shoulder therebetween, and a bottom with a cylindrical aperture therethrough thus forming an interior shouldered recess, a lug 65 projecting inwardly above the bottom of

said recess, a handle-equipped plunger rod reciprocable through said aperture and having a flange adapted to rotate under said lug and recessed to pass thereover, said flange also having means thereon adapted 70 to contact said lug when the flange is disposed therebeneath and the rod is rotated and a gasket with which said exterior shoulder engages.

6. The combination with a sprayer receptacle having a threaded opening therein and a flange extending inwardly around said opening, of a closure member having portions of different diameter exteriorly threaded, thus forming a shoulder therebetween, a pump cylinder having an outwardly curved edge adapted to be received on one of said portions and to fit against said shoulder, the other of said portions being adapted be screwed into said threaded opening, a gasket disposed on said flange against which said edge contacts to seal said receptacle.

7. The combination with a sprayer receptacle having a threaded opening therein, of a hollow cylindrical member having portions of two different diameters exteriorly threaded forming an exterior shoulder therebetween and having a shouldered recess therein, a lug projecting inwardly from one of said portions above the bottom of said recess, said member having an aperture through its bottom, a pump cylinder adapted to be screwed onto the portion of smaller diameter and the portion of larger diameter being adapted to be screwed into said threaded opening, a gasket against which said exterior shoulder rests, a plunger rod reciprocable through said aperture, a handle secured to said rod and having a flange adapted to rotate beneath said lug, said flange having an upstanding lug adapted to contact with the sides of the first mentioned lug and turn said closure member, and said flange also having a recess adapted 100 to pass over said first mentioned lug.

8. A sprayer device having in combination a receptacle having a threaded opening therein, a closure member for said opening having a threaded portion adapted to be 115 screwed into said threaded opening, said member having a threaded portion of reduced diameter below said first mentioned portion forming a shoulder, a pump cylinder having its upper end interiorly threaded to receive said latter portion and be closed by said shoulder, said closure member having a central opening therethrough, a handle-equipped plunger rod reciprocable through said opening, and means thereon 120 engaging with said closure member whereby the latter can be screwed into or out of said threaded opening and into or out of said pump cylinder by a turning movement of said handle, and a gasket against which 130

said shoulder may be screwed by said handle-equipped plunger.

9. The structure set forth in claim 8, said closure member being hollow, and means projecting therein with which the means on said rod engages, the means on said rod being adapted to be disposed within said closure member.

10. A closure member for the threaded opening of a sprayer receptacle comprising a hollow cylindrical member having exteriorly threaded portions of different diameters forming a shoulder therebetween, an open top and a closed bottom, the latter having a central opening therethrough said member thus having a shouldered recess therein, and a lug projecting inwardly from the walls of said recess above the bottom thereof.

20 11. The combination with a sprayer receptacle having an opening therein and a pump cylinder adapted to be disposed in said receptacle, of a closure member for said receptacle and pump cylinder having portions adapted to fit in said opening and pump cylinder and movable to position therein by a turning movement, said portions having a shoulder therebetween and a

gasket against which said shoulder rests to seal said receptacle and pump cylinder. 30

12. The structure set forth in claim 11, and a plunger rod movable through said closure member and having means therein engageable with said member to turn the same.

35 13. The combination with a sprayer receptacle having an opening therein and a pump cylinder adapted to be disposed in said receptacle, of a closure member for said receptacle and pump cylinder having portions adapted to fit in said opening and pump cylinder and movable to position therein by a turning movement, said portions having a shoulder therebetween, a gasket against which said shoulder rests to seal said receptacle and pump cylinder, and a plunger rod movable through said closure member and having means thereon engageable with said member to turn the same, said closure member being hollow and having means on the interior thereof adapted to be engaged by said means on the plunger rod.

40 45 50 In testimony whereof I affix my signature.

HENRY E. BRANDT.
